UNITED STATES PATENT OFFICE

DAVID FISHER, OF PADEN CITY, WEST VIRGINIA, ASSIGNOR TO PADEN CITY GLASS MANUFACTURING COMPANY, OF PADEN CITY, WEST VIRGINIA, A CORPORATION OF WEST VIRGINIA

DESIGN FOR A COMPARTMENT TRAY

Application filed February 5, 1930. Serial No. 34,412. Term of patent 3½ years.

To all whom it may concern:

Be it known that I, DAVID FISHER, a citizen of the United States, residing at Paden City, in the county of Wetzel and State of West Virginia, have invented a new, original, and ornamental Design for Compartment Tray, of which the following is a specification, reference being had to the accompanying drawing, forming a part thereof.

Fig. 1 is a perspective view of a compartment tray showing my new design; Fig. 2 a plan view thereof; and Fig. 3 a side view thereof.

I claim:

The ornamental design for a compartment tray, as shown.

DAVID FISHER.
